UNITED STATES PATENT OFFICE.

JAMES TIMMS, OF COLUMBUS, OHIO, ASSIGNOR TO THE BUCKEYE MALLEABLE IRON AND COUPLER COMPANY, OF SAME PLACE.

CAR-COUPLING.

SPECIFICATION forming part of Letters Patent No. 606,603, dated June 28, 1898.

Application filed December 17, 1897. Serial No. 662,308. (No model.)

To all whom it may concern:

Be it known that I, JAMES TIMMS, of Columbus, in the county of Franklin and State of Ohio, have invented certain new and useful 5 Improvements in Car-Couplings; and I do hereby declare the following to be a full, clear, and exact description of the invention, such as will enable others skilled in the art to which it appertains to make and use the same.

10 My invention relates to an improvement in car-couplings, and more particularly to that variety known as "tender-couplings," in which the draw-bar is necessarily short in consequence of the fact that the coupling has 15 to be supported solely from the end of the tender and cannot extend for an indefinite length beneath it, the object being to provide additional support besides that afforded by the draw-bar or shank of the coupling; and 20 the invention consists in an overreaching arm extending from the draw-head to some point above the bracket which supports the coupling.

It further consists in certain novel features 25 of construction and combinations of parts, which will be hereinafter described, and pointed out in the claims.

In the accompanying drawings, Figure 1 is 30 a vertical sectional view through the coupling and bracket. Fig. 2 is a front view of the bracket, and Fig. 3 is a top view of the pin-head.

A represents the draw-head. This has the usual shank 1, by which it is pivoted, and 2 25 is the arm which gives the added support to the coupling and prevents it from sagging. This arm is preferably cast integral with the draw-head. It extends upward to clear the top of the bracket and then inward and in 35 line with the pin-hole 3 in the shank or draw-bar. It is also provided with a hole 4. To afford added strength to this arm, it is furnished with a central longitudinal rib 5, and it may likewise have ribs 6 at its edges to give 40 additional strength.

C is the bracket, secured to the end of the tender and upon which the coupling is supported. This bracket comprises a vertical plate 7, having bolt-holes 8 at convenient 45 points therein to receive securing-bolts. At the bottom it preferably has the horizontal portion 9, which extends beneath the sill.

Plate 7 may also have the offset 10, which is sunk into a recess formed in the end of the car. Projecting forwardly from the plate 7 55 is the mouth 11, in which the shank extends. This mouth may be internally ribbed, as at 12 12, to give it strength, and also it may be furnished with the receptacles 13 13 for springs to hold the coupling yieldingly centered.

The pin D is of the usual construction, except that its head instead of being perfectly round has at least one straight edge 14, or, if not straight, of such construction that it 65 rests against plate 7 when in place, and by its engagement therewith is prevented from turning.

It is evident that slight changes might be made in the form and arrangement of the 70 several parts described without departing from the spirit and scope of my invention, and hence I do not wish to limit myself to the exact construction herein set forth; but,

Having fully described my invention, what 75 I claim as new, and desire to secure by Letters Patent, is—

1. In a car-coupling, a draw-head having a shank or draw-bar and an arm extending from the draw-head upwardly over the shank in 80 position to receive the pin which holds the draw-head in place and prevents the latter from sagging.

2. The combination with a bracket having a mouth projecting outwardly therefrom, of 85 a draw-head having a shank and an arm extending above the shank and a suitable distance from it, and means for pivotally connecting the draw-head so as to permit it to have normally a lateral movement. 90

3. The combination with a bracket and a draw-head, of a pin connecting the draw-head pivotally to the bracket, said pin having a head extending from one side and squared, so that it rests and fits against the bracket to 95 prevent the rotation of the pin.

In testimony whereof I have signed this specification in the presence of two subscribing witnesses.

JAMES TIMMS.
